UNITED STATES PATENT OFFICE.

FRANZ WALTHER, OF BERLIN, GERMANY.

METALLIC CONSTRUCTIONAL TOY.

Application filed February 26, 1925, Serial No. 11,845, and in Germany January 29, 1924.

This invention relates to the formation of a tube which is to be employed as a shaft, an axle, a roller, a column, a girder or the like in a metallic structural set, to the connecting thereof with other structural members, and to the supporting thereof.

When assembling metallic structural toys the parts of which are worked according to a unitary proportion and prepared in advance for assembly, perforated for example, it is preferable so to shape the individual structural elements that as few different members as possible are required, and that these permit of the most varied possible employment for the manifold models to be produced out of the constructional set.

In the case of the thin axles and shafts hitherto employed for constructional toys it is a disadvantage that the main shaft in the case of one model, for example of a heavy steam engine, is just as thick as the shaft of a governor or of an oil pump inserted in the same model. On this account, according to the invention, a shaft of larger diameter 25 is made as a tube.

This tube is made, according to the invention, by bending round or rolling up a plate of thin metal, in which are provided regularly distributed slot-like holes, which serve 30 for the reception of the hook clips and fixing clips which are specially shaped for this purpose. By means of these clips, wheels, wheel rims, rings, discs, spokes, flat iron bars, strips and other perforated structural members are connected with the tube. Instead of the slot-like holes, or besides them, holes of other forms may be provided in the tube, such as round, rectangular or oval holes, as in other parts of the set.

40 For the supporting of the tube there is provided a ring support consisting of a simple ring with a perforated disc. This may be shaped round, or angular, or partly round and partly angular. The ring support is also usable as a pedestal for the tube when the latter is used as a column; or a special journal member is fitted into the end 45 of the tube. With such journals at both ends the tube is also adapted for use as a roller.

In the accompanying drawings are illustrated various constructional forms of the invention and of its parts.

55 Figure 1 is a longitudinal elevation of the tube *c* with the slot-like holes *d*.

Figure 2 shows how flat hook clips *a* and bent or twisted hook clips *b* are inserted in the tube *c*, which is shown in section.

Figure 3 shows a piece of tube *c* in longitudinal section, with an inserted flat hook 60 clip *e*, bent hook clip *f* and flat fixing clip *g*. In the case of the hook clips *e* and *f* there is a notch *e*₁ above the foot, and the foot has projections *e*₂ on both sides, which bear against the inner wall of the tube. In the 65 case of the fixing clip *g* are provided, above the foot, on both sides, projections *g*₁, which bear against the outer wall of the tubes.

Figure 4 shows the tube *c*, to which is fastened by means of the two bent fixing clips 70 *h* and of the screws *i* the string wheel (rope pulley) *k*.

Figure 5 shows the same in cross-section. By means of the projections *h*₁ above the foot of the bent fixing clips *h* the latter 75 bear against the outer wall of the tube.

Figure 6 shows in elevation in the upper half and in section in the lower half the tube *c* in a simple ring support, consisting of a plane supporting disc *l* and a cylindrical part *m*.

Figure 7 is a front elevation of this support. The holes *n* in the supporting disc serve for connecting it to other structural members.

Figure 8 shows a bearing journal *o* for insertion into the end of the tube, with slots *p* in the insertion member *q* for fastening it into the tube *c* by means of flat wedges *r*, split pins or the like, which are stuck into 90 the holes *d* and *p* in the tube *c* and the insertion member *q*.

What I claim is:—

1. A tubular structural member for metallic constructional toys and means for supporting it and connecting it with other structural members, said member consisting of a piece of sheet metal tubing formed with slot-like holes adapted to engage with other structural members, and said connecting means consisting of hook clips and eye clips.

2. A hook clip for connecting tubular structural members according to claim 1, the breadth of the clip being about equal to the length of a slot in the tube, said clip comprising a foot projecting on both sides beyond the edge of the clip and being formed with a notch on one side above said foot, the width of said notch being 110

equal to the thickness of the tube wall, so that the projections are adapted to bear against the internal surface of the tube.

3. A fixing clip for connecting tubular structural members according to claim 1, further comprising above the foot of the clip, on both sides, projections which are adapted to bear against the external surface of said tubular member.

10 4. A support for a structural member for metallic constructional toys, said member consisting of a piece of sheet metal tubing with slot-like holes adapted to engage with other structural members, said support comprising a plane part and a cylindrical part rigidly connected to said plane part, the mean radius of the cylindrical part differing from the mean radius of the tubular member by an amount equal to the thickness of the metal of which they are composed.

15 5. A support for a structural member for metallic constructional toys, said member consisting of a piece of sheet metal tubing with slot-like holes adapted to engage with other structural members, said support comprising a perforated plane annular

part adapted to be slipped over the outside of the tubular member, and a cylindrical part rigidly connected to said plane part, the mean radius of the cylindrical part being greater than the mean radius of the tubular member by an amount equal to the thickness of the metal of which they are composed.

35 6. A support for a structural member for metallic constructional toys, said member consisting of a piece of sheet metal tubing with slot-like holes adapted to engage with other structural members, said support comprising a plane part, a cylindrical part rigidly connected to said plane part, and a journal pivot secured externally and axially to said plane part, the mean radius of the cylindrical part being less than the mean radius of the tubular structural member by an amount equal to the thickness of the metal of which they are composed, and the cylindrical part of the support being formed with slots to enable it to be keyed to the tubular member.

In testimony whereof I have signed my name to this specification.

FRANZ WALTHER.
